UNITED STATES PATENT OFFICE.

HENRY BARKSCHAT, OF LOS ANGELES, CALIFORNIA, ASSIGNOR TO MARBELITE CORPORATION OF AMERICA, OF LOS ANGELES, CALIFORNIA, A CORPORATION OF DELAWARE.

MOLDING MACHINE.

Application filed March 29, 1926. Serial No. 98,175.

This invention has to do generally with machines for molding plastic material by the well known centrifugal method, and has as its principal object to provide a machine 5 which includes a cast metal mold, there being provisions in connection with the machine proper and the mold which render the use of such cast metal molds feasible. In order that a clear understanding may 10 be had of inventor's advance in the art it may be well to point out very briefly certain prior developments. When castings were first made by the centrifugal method, the molds were made up of wood, this for 15 the reason that the inner mold faces could be carved and otherwise worked to produce fairly intricate designs which were to appear on the external face of the cast article. When such molds were used in connection with the casting of such massive 20 articles as ornamental light posts, and the like, it was found that they could not withstand the severe service conditions arising from the necessity for tightly gripping the 25 mold in the centrifuges, rotating the molds at high speed, and assembling and disassembling the molds between each casting operation. The next step was to produce 30 sheet metal molds, but it proved very difficult to secure many fine intricacies or details of designs in metals of a thickness sufficient to stand up under the severe service 35 conditions. Then came the cast iron mold which was gripped directly by the chuck jaws of the centrifuges. In revolving these 40 molds at high speeds there was very considerable vibration set up in the centrifuges and consequently transmitted directly to the cast metal molds. The sharp, rapid vibration soon fatigued and crystallized the 45 molds to such an extent that they were worthless after but comparatively few successive operations. Except for their tendency to crystallize, the cast-metal molds were found vastly superior to either wood or sheet metal molds. Applicant has made 50 possible the use of cast metal molds by interposing members having a degree of yieldability or resiliency between the chuck jaws and body of the cast metal mold, the drive between the chucks and mold thus being transmitted through this resilient medium, which is preferably wood. The wood is 55 found to absorb and take the sharpness from the vibrations to such an extent that cast 55 metal molds equipped therewith are capable of standing up indefinitely, as inventor has proven by continued practice. Inventor has also found that by gyrating one end of the mold with respect to the 60 other, that the disengagement of excess water from the plastic mass is hastened, that the compacting of the aggregate deposited on the mold walls is effected more 65 quickly and solidly, and that "classification" of the constituents of the plastic mass is avoided. This gyration naturally gives added movement to the centrifuges and 70 mold, but the wood or resilient member between the mold body and the chuck jaws 75 reduces the sharpness of this vibration as imparted to the metal of the mold to such a degree that the metal does not become quickly crystallized. In a copending application entitled 75 "Molds for concrete posts and the like", filed by the present inventor February 24, 1925, Serial No. 11,052, applicant has shown and claimed a mold constructed in accordance with the above, and has there claimed 80 a particular manner of securing the wooden sheathing to the mold body. In the present application he is claiming the combination of a centrifuge and a cast metal mold so encased, or more broadly speaking, of a 85 centrifuge and a cast metal mold body between which and the driving element of the centrifuge is interposed a resilient member. Further objects and novel features of the 90 invention will be made apparent in the following detailed description, reference being had to the accompanying drawings in which: Fig. 1 is a side elevation of a machine embodying my invention; Fig. 2 is an end elevation of Fig. 1; Fig. 3 is a diagrammatic view illustrating 95 certain characteristics which the machine may possess; Fig. 4 is an elevation of a mold made in accordance with this invention; Fig. 5 is a section on line 5—5 of Fig. 4; and Fig. 6 is a section on line 6—6 of Fig. 5. I will first describe the mold shown in 100 Figs. 4 to 6, inclusive, this mold being adapted to cast concrete lamp posts having well defined cap and base portions, but it will be understood the invention, in its broader 105

aspects, is equally applicable to molds for casting shafts of uniform or gradually diminishing diameters throughout their longitudinal extent. The metal shell of the mold is made up of a shaft-like body A having at opposite ends the base B and cap C. The shell is parted longitudinally to form a plurality of separable sections 10. Each section is made up of shaft portion 11, which I will hereinafter term the body portion of the mold section, base portion 12 and cap portion 13, the portions being bolted together more or less permanently so each section may be handled as a unit handling the assembly and knocking down of the mold. In other words, while each section is made up of separable parts, the parts are not usually uncoupled except for replacement or repair. The material of which the sections are cast is not material to this invention, though I have used both cast iron and cast aluminum, the latter being preferable due to its relative lightness, and ductility, these being important characteristics when it is remembered that the molds are ordinarily of very considerable length and diameter and are exposed to severe vibration.

It is not necessary to the present invention that the provisions for joining the section portions be of the type illustrated, although the drawings show a connection which is particularly well adapted for use with the sheathing or resilient vibration absorber shown in the drawings. Therefore, while I will describe the illustrated connection between the portions, this is not to be construed as limitative on my broader claims.

Body portions 10 have end flanges 14, 15, which are adapted to be bolted at 14^a to end flanges 16 and 17 of base portions 12, and 13, respectively. Extending from flanges 16 and 17 are band flanges 18 which extend over the edges of flanges 14, and 15, and over the outer peripheral faces of body portions 11 to provide sockets 19 at both ends of each body portion.

Wood sheathing is applied to the outer faces of the metal body portions, and while the invention is not so limited, it is preferable that this sheathing extend from end to end of said portions. For instance, a strip of wood sheathing 20 may extend longitudinally over each body portion, the ends of the strip being set in sockets 19 and secured in place by screws 21 which are countersunk in flanges 18, or they may be merely friction tight within the sockets. The inner faces of the wood strips are preferably formed substantially complementary to the outer faces of the body portions, while the outer faces of the strips preferably are substantially arcuate. The strips may be cut away or notched at 22 to give access to bolts 23 which connect side flanges 24, the latter extending longitudinally along the parting

lines of the mold. These bolts serve to hold the several mold sections 10 in assembly during casting operations and are removed to allow the mold to be opened up after the concrete therein has taken sufficient set. 70 After the mold sections are bolted together, bands 25 are clamped therearound to hold the sheathing snugly to the metal shell at points intermediate their end attachment; there then being no liability of the sheathing becoming loosened or moving away from the metal shell when the mold is being revolved by the centrifuge. 75

The outer peripheral faces of band flanges 18 are preferably covered with bands of 80 heavy fabric or belting F to provide a good gripping surface for the centrifuge chucks (to be later described) which engage the molds at these points; flanges 18 serving thus not only as holders for the ends of the 85 sheathing strips, but also as chuck engagement members.

Both the wood strips where they enter the sockets, and bands F provide resilient members between the centrifuge chucks and the cast metal body A or body portions 11, so that vibrations set up by the machine and existing in the chucks are somewhat damped or softened before they reach the cast metal body portions, this relief of the body portions from excessively sharp vibrations contributing greatly to the useful life thereof. Where the wooden strips are longitudinally co-extensive with the body portions, as shown, they also serve as reinforcement members for said body portions and distribute the vibrations from the driving members of the centrifuges longitudinally along the mold rather than allowing such vibrations to become concentrated at the point of driving engagement between the centrifuge and mold, thus tending to decrease the liability of the mold casting becoming crystallized or unduly fatigued. 105

While the particular type of centrifuge used in combination with the mold is not essential to the present invention, the type illustrated is especially well adapted to the purpose, and has certain features which particularly call for the protection of the mold against destructive vibration.

Centrifuge 26 is made up of two substantially identical units 27 and 28, these units having cylindrical mold carriers or open ended drums 29 and 30, which carry chuck jaws 31 and 32, respectively. These jaws are arranged in any suitable manner (not shown, since any suitable jaw actuating means are well known to those skilled in the art) and are adapted to engage drivingly the mold bands F. The jaws are movable in any well known manner (not shown) to allow easy insertion and withdrawal of the mold. 120

Each drum is operated by rollers 33 which are journaled on frames 34 and engage 125

drum roll ways 35 in the usual manner, units 27 and 28 ordinarily being set up so the drum axes are approximately alined.

In order that frames 34 need not be built excessively heavy to withstand the vibrations set up by the drums during rotation thereof, it is preferable that roller shafts 33^a be yieldably mounted in the frames. For instance, they may be mounted in the manner set forth in United States Letters Patent No. 1,391,164, issued to me September 20, 1921; shaft boxes 35 being slidably mounted in the frame for movement radially toward and away from the drum axes and being urged toward said axes by adjustable springs 36. Belts 37 are run over crowned portions 38 of the drums and are driven from power shaft 39 by pulleys 40. While the drawings indicate that both drums are positively driven, it is usually desirable to apply power to one only, the other merely being guided in its movement by the associated set of rollers 33.

While the vibrations set up in jaws 31 and 32 by rotation of the drum are considerable, they are damped before they reach the body portions of the mold by the fabric bands F and wood strips 20. These vibrations of the chuck jaws are aggravated and consequently there is more need to dampen them when the centrifuges are made in accordance with the disclosure of the patent issued to me on July 7, 1925, for "Machine for molding concrete posts and the like" No. 1,544,879.

I have here indicated in Fig. 3 that the centrifuge of the instant application is similar to the one shown in the last mentioned patent, though this is not limitative on the present invention. It will serve to illustrate, however, a case where it is particularly essential that the vibrations between the driving member of the centrifuge and the cast metal body portion of the mold be damped or absorbed. As set forth in said last-mentioned patent, it is found that by gyrating one end of the mold with respect to the other, the disengagement of the excess water in the plastic mass is hastened, that the aggregate deposited on the mold walls is compacted more quickly, and that the concrete is kept from "classifying". Alteration of the machine or mold to accomplish such gyration may be accomplished in a variety of manners, but I have here chosen to show but a single method. Referring to Fig. 3 chuck jaws 32 in drum 30 are adapted to hold one of the bands F concentrically

within said drum, while jaws 31 in drum 29 are offset with respect to the axis of rotation of said last-named drum and, therefore, hold the left-hand end of the mold (as viewed in Fig. 1) eccentrically within said drum. Drum rotation consequently gyrates the ends of the mold with respect to one another (the chuck jaws being arranged in any suitable manner, not shown, to grasp the mold collars or bands in a manner to allow this relative movement of the mold ends) with the advantageous effects mentioned above. This gyration naturally causes sharper vibrations of the chuck jaws where they drivingly engage the mold, but such vibrations are softened before they reach the mold body due to the presence of the resilient fabric bands F or the wood sheathing or both.

It will be understood the drawings and description are to be considered merely as illustrative of and not restrictive on the broader claims appended hereto, for various changes in design, structure and arrangement may be made without departing from the spirit and scope of said claims.

I claim:

1. In a machine of the character described, a pair of spaced and substantially axially alined centrifuge units having mold taking chucks, a mold having a body portion of cast metal, and relatively resilient elements on the mold and interposed between the body portion and the jaws of the chucks.

2. In a machine of the character described, a pair of spaced and substantially axially alined centrifuge units having mold taking chucks, a mold having a body portion of cast metal, and wood sheathing on the body portion and interposed between said portion on the jaws of the chucks.

3. In a machine of the character described, a pair of spaced and substantially axially alined centrifuge units having mold taking chucks, an elongated mold having a body portion of cast metal wood sheathing extending longitudinally from end to end along the body portion and interposed between said portion on the jaws of the chucks; and means for holding the sheathing in tight engagement with the external face of the body portion.

In witness that I claim the foregoing I have hereunto subscribed my name this 8th day of March 1926.

HENRY BARKSCHAT.
